UNITED STATES PATENT OFFICE.

CHARLES J. THOMSON, OF PHILADELPHIA, PENNSYLVANIA.

FASTENING DEVICE FOR ELECTROTYPE.

1,139,925.

Specification of Letters Patent.

Patented May 18, 1915.

Application filed January 14, 1915. Serial No. 2,099.

To all whom it may concern:

Be it known that I, CHARLES J. THOMSON, a citizen of the United States of America, residing in the city and county of Philadelphia, in the State of Pennsylvania, have invented certain new and useful Improvements in Fastening Devices for Electrotype, of which the following is a true and exact description, reference being had to the accompanying drawings, which form a part thereof:

My present invention consists in a novel and effective fastening device primarily devised for use in detachably securing electrotype or other printing plates to the slotted or other plate supporting members of printing presses.

The various features of novelty which characterize my invention are pointed out with particularity in the claims annexed to and forming a part of this specification. For a better understanding of the invention, however, and of the advantages had with it, reference should be had to the accompanying drawings and descriptive matter in which I have illustrated and described a preferred embodiment of my invention.

Of the drawings: Figure 1 is a plan view of a portion of the cylinder of a printing press on which my invention is employed. Figs. 2 and 3 are partial sectional elevations taken respectively on the lines 2-2 and 3-3, of, and on a larger scale than, Fig. 1. Fig. 4 is a perspective view of my novel fastening device.

In the drawings, A represents the body of a well known type of printing press cylinder or cylinder segment. The cylinder A is formed with under cut peripheral slots A' extending parallel to the axis of the cylinder. In the actual type of construction illustrated these slots are formed by the spaces between I-bars B each of which has its base received, and calked in a corresponding longitudinal groove A² in the cast metal body portion of the cylinder A.

C represents an electrotype or similar plate which is detachably secured against the cylinder A by means of my novel fastening devices D. Each fastening device D, in the form shown, comprises a body portion d of a thickness to fit easily between the adjacent edges of the outer flanges B' of an adjacent pair of rails B. The body portion d of the fastening device is provided at one end with a laterally enlarged head d²,

the lateral trunnion like extensions d⁴ of which bear against the inner sides of the corresponding flanges B'. To the opposite end of the body portion d of the fastening device is secured a spring clip D' which, as shown, is U shaped. The legs of the clip D' enters the slots A' at the opposite sides of the slot A' receiving the body portion d of the fastening device. As shown, the legs 65 of the spring clip D' are inturned to better engage and grip the corresponding flanges B', as shown best in Fig. 2. Between its ends the portion d is formed with a finger d' which when the fastening device is employed 70 as shown in the drawings, bears against the outer side of the reduced flange, or edge of the plate C, and thereby clamps the latter against the support A.

In the use of the improved fastening device, the head d² is first entered in the corresponding slot A' with the trunnions d⁴ extending parallel to the length of the slot, as shown in Fig. 2. The fastening device is then given a quarter turn to bring the part d 75 into the position in which its plane is radial with respect to the cylinder A, and the device is then moved into the position shown in dotted lines in Fig. 3, in which the finger d' extends over the flange C' of the plate C, 80 and the body d extends at an angle to the axis of the cylinder A. The fastening device is then secured in place by pressing the outer end of the body d inward until the body d extends generally parallel to the 85 length of the axis of cylinder A as shown in full lines in Fig. 3. The fastening device is yieldingly held in this position by the inturned edges of the spring clip D' which bear against, and curl under the remote 90 edges of the flanges B' of the rails B between which the body portion d of the fastening device is received.

As the fastening device is moved from the dotted line position of Fig. 3 into the 100 full line position of that figure, the part d forms a lever of the second class with the fulcrum the portions of the flanges B' engaged by the lateral extensions d⁴. The leverage thus had makes it readily feasible 105 for the fastening devices to be moved into place by the fingers of the operator and increases the effectiveness of the spring clips D' as holding devices.

To permit of the rotation of the member 110 d from the dotted to the full line positions of Fig. 2, the member is advantageously

formed with a rounded neck portion d^3 . To facilitate the ready putting in place and removal of the fastening device, the width of the space under the finger d' receiving 5 the flange portion C' should be appreciably thicker than the latter. As shown, the member d is a flat piece of sheet metal and the spring clip D' is secured thereto by rivets d^3 , while the lateral trunnion like extensions d^4 are formed by the ends of a pin passed through the head d^2 . It will be obvious, however, that my invention does not depend on how the different parts of the fastening device are connected together; or 10 on whether the device is made of several parts secured together; or in one integral piece. It is desirable, however, that the spring clip portion D' should possess considerable resiliency and I prefer, also that 15 the finger d' , and the portion of the member d between the finger d' and head d^2 should possess some resiliency, and the fastening device as a whole may advantageously be made out of wrought steel.

20 25 In the use of my device to secure an electrotype or other plate in place, as many fastening devices may be employed as are necessary for the purpose. In securing a comparatively small plate in place, four fastening devices, one engaging the plate adjacent each corner as shown in Fig. 1, are ample. With larger plates more than two fastening devices at each side edge will ordinarily be employed.

30 35 While in accordance with the provisions of the statutes, I have herein described and illustrated the best forms of my invention now known to me, it will be apparent to those skilled in the art that changes can 40 be made in the form of my invention without departing from its spirit, and that some features of my invention can be used in some cases without a corresponding use of other features of the invention.

45 50 Having now described my invention, what I claim as new and desire to secure by Letters Patent, is:

1. A plate fastening device of the kind specified comprising a body portion provided with a laterally enlarged head at one end, and at the other end with a spring clip and having a finger extending from said body portion in a direction generally parallel to the length of the latter from a point

intermediate its ends, said finger being separated from said body portion by a plate receiving space and being adapted to bear against the side of a plate inserted in said space at some distance from the inserted edge of said plate. 55 60

2. In combination with a support formed with an undercut groove, of a device for securing a plate against said support, said device comprising a portion adapted to project into said groove and extend under the plate, and formed with a laterally enlarged head at one end adapted to bear against the undercut walls of said groove, and provided at its other end with means adapted to engage, and yieldingly hold that end of the 70 device against movement outward from said support, and provided with a finger intermediate said ends adapted to project over the edge of the plate and engage the upper side of said plate at some distance 75 from its margin and press said plate directly toward said support.

3. In a printing press, the combination with a support formed with parallel undercut grooves, of a device for securing a plate 80 against said support comprising a body portion having a laterally enlarged head adapted to be inserted in one of said grooves when the lateral enlargements of said head extend parallel to the length of 85 the groove and to be rotated with said head so inserted to bring said lateral enlargements transverse to the length of the groove, said lateral enlargements being then adapted to bear against the inner edges of the 90 under cut walls of the groove to prevent the removal therefrom of said head, a spring clip secured to the opposite end of said head from said body portion and having portions adapted to enter the grooves 95 at the opposite sides of the groove at which said head is entered to yieldingly hold the corresponding end of said body portion against movement outward from said portion, said body portion being formed with a 100 finger projecting from it between its ends and adapted to lie or bear against the side edge of said plate to thereby hold the latter against said support.

CHARLES J. THOMSON. [L. S.]
